Attorney

UNITED STATES PATENT OFFICE.

GEORGE SHERMAN CLARK, OF HUNTINGTON, WEST VIRGINIA, ASSIGNOR, BY MESNE ASSIGNMENTS, TO CLARK PATENT TUBING CO., OF WHEELING, WEST VIRGINIA, A CORPORATION OF WEST VIRGINIA.

BLASTING TUBE AND BLASTING-TUBE PACKAGE.

Application filed February 10, 1922. Serial No. 535,643.

To all whom it may concern:

Be it known that I, GEORGE S. CLARK, a citizen of the United States, residing at Huntington, in the county of Cabell and 5 State of West Virginia, have invented certain new and useful Improvements in Blasting Tubes and Blasting-Tube Packages; and I do hereby declare the following to be a full, clear, and exact description of the invention, such as will enable others skilled in the art to which it appertains to make and use the same.

In the mining industry the cartridges are formed in the mine when required for use, 15 the miner utilizing a strip of paper which is wrapped about a mandrel into tubular form from which he makes the shell for receiving the blasting charge.

This practice has not been wholly satisfactory in results and is yielding to a 20 method in which the miner is supplied with a tube strip from which a portion is severed to form a cartridge shell of required length.

The present invention relates to the 25 method of forming the tube strip into a package of convenient shape and size for handling, to the tube package and to the tube which embodies a combined sealing and gage strip whereby the required length of 30 tube may be easily determined and whereby the tube is rendered tight and the package close.

In constructing the tube a strip of paper or other suitable material has its opposite 35 edge portions folded inwardly and overlapped on a central line whereby to form a tube of flattened form. A sealing strip is applied and secures the overlapped edge portions of the tube strip. The adhesive applied 40 to the sealing strip dampens and causes the same to expand. The sealing strip when applied occupies a central position at one side of the tube strip and the latter is wrapped upon itself to form an oblong package with 45 the sealing strip on the out side of the windings so that upon contracting when drying it obtains a tight joint and a close package.

Other objects and advantages will be apparent and suggest themselves as the nature 50 of the invention is understood.

While the drawings illustrate an embodiment of the invention it is to be understood that in adapting the same to meet different

conditions and requirements, various changes 55 in the form, proportion and minor details of construction may be resorted to without departing from the nature of the invention.

Referring to the accompanying drawings forming a part of the application, 60 Figure 1 is an elevation of a miner's blasting tube package embodying the invention,

Figure 2 is a top plan view thereof, 65 Figure 3 is an end view of the package, and

Figure 4 is a perspective view of the package with an end portion of the tube strip extended.

Corresponding and like parts are referred to in the following description and designated in the several views of the drawings by like reference characters.

The numeral 1 designates a flat tube strip 75 constructed in accordance with the invention and formed into an oblong package, as indicated most clearly in Figures 1 and 4, the outer end of the tube being made secure by a fastening strip 2 secured thereto by a suitable adhesive. The flat tube 1 is 80 formed of a strip of paper or other suitable material having its longitudinal edge portions folded with the marginal edge portions overlapping. A sealing strip 3 is applied to the overlapping marginal portions of the 85 strip to secure the same, the sealing strip being secured to the tube strip by a suitable adhesive during the process of forming the tube. The application of the adhesive to the sealing strip 3 results in a dampening and 90 expansion of the strip which is applied to the tube while still damp and expanded. The tube is formed in a continuous length and simultaneously with the formation of the tube, the latter is rolled or wrapped upon itself 95 so as to form an oblong package, as indicated most clearly in Figures 1 and 4. The tube is so rolled or wrapped that the side having the sealing strip 3 applied thereto is disposed outwardly, whereby to occupy 100 the outside of the respective windings or folds. After a package of predetermined size has been formed, the tube strip is severed and the end of the tube is made secure by means of the fastening strip 2. During

105 the drying of the sealing strip 3, the latter contracts thereby insuring a tight joint and at the same time the formation

of a close package, since the several winds or folds contract and are brought into closer relation thereby forming a compact and tight package.

- 5 The sealing strip 3 is provided in its length with graduations whereby to facilitate determining the length of the portion of the tube to be severed in order to form a shell to receive the blasting charge when
- 10 preparing a cartridge of required length. The oblong form of the package adds to the convenience and ease of handling the same in the mine and does not materially incommod the miner in carrying the same
- 15 about the person.

It will be understood that the invention is not limited to the illustrated embodiment but is subject to various modifications. For example, two strips of paper and

- 20 two sealing strips may be used in the case of large tubes.

What is claimed is:

1. The method of forming a blasting tube package, which includes forming a flat tube 25 by folding the edges of a flat strip towards one another, applying a damp sealing strip to the tube to secure the edge portions thereof and wrapping the flat tube upon itself to form a package with the sealing 30 strip outside, whereby the subsequent drying and contracting of the strip insures the formation of a tight package.

2. The method of forming a blasting tube package, which includes forming a flat tube by folding the edges of a flat strip towards 35 one another, applying a damp sealing strip to the edge to secure the edge portions thereof and wrapping the flat tube upon itself to form an oblong package with the sealing strip outside, whereby the subsequent drying 40 and contracting of the strip insures the formation of a tight package.

3. A blasting tube package formed from a flat tube having a sealing strip applied to the tube and lying on the outside of the 45 wrappings, the strip being applied to the tube while still damp and the package thereupon wrapped to form a tight package, the tube being adapted to be drawn laterally from the center when required for use without releasing the outer end of the tube.

4. A blasting tube package formed from a flat tube having a sealing strip applied to the tube and lying on the outside of the 50 wrappings, the strip being applied to the tube while still damp and the package thereupon wrapped to form a tight package, the tube being adapted to be drawn laterally 55 from the center when required for use without releasing the outer end of the tube, and linear graduations on the tube for indicating the length withdrawn from the package.

In testimony whereof I affix my signature,
GEORGE SHERMAN CLARK.
